CLAIM

The ornamental design for child's toy, as shown and described.

DESCRIPTION

FIG. 1 is a front view from above and one side of a child's toy embodying my novel design;

FIG. 2 is a front view of another embodiment of the child's toy embodying my novel design;

FIG. 3 is a rear view of the embodiment shown in FIG. 2;

FIG. 4 is a top plan view of the embodiment shown in FIG. 2;

FIG. 5 is a side elevational view of the embodiment shown in FIG. 2, the opposite side being a mirror image thereof.

FIG.1
